(57) **CLAIM**

The ornamental design for a fifth wheel cover, as shown and described.

DESCRIPTION

FIG. 1 is a perspective view of a fifth wheel cover showing my new design;

FIG. 2 is a top view thereof;

FIG. 3 is a bottom view thereof;

FIG. 4 is a side view (opposite side view is mirror image) thereof;

FIG. 5 is a front view thereof;

FIG. 6 is a back view thereof; and,

FIG. 7 is a cross-sectional view of FIG. 3.

In FIG. 1 and FIG. 2, the broken lines illustrate portions of the article and form no part of the claimed design.

In FIGS. 1-6, the broken lines represent stitching but do not form part of the claimed design.

1 Claim, 4 Drawing Sheets

FIG. 1

FIG. 5

FIG. 6

FIG. 4

FIG. 7
